UNITED STATES PATENT OFFICE

162,120

MERCHANDISE DISPLAY HOLDER

Frank V. Brach, Glenview, Ill., assignor to E. J.
Brach & Sons, Chicago, Ill., a corporation of Illinois

Application October 6, 1949, Serial No. 5,319

Term of patent 14 years

(Cl. D80—9)

To all whom it may concern:

Be it known that I, Frank V. Brach, a citizen of the United States, residing at Glenview, in the county of Cook and State of Illinois, have invented a new, original, and ornamental Design for a Merchandise Display Holder, of which the following is a specification; reference being had to the accompanying drawing, forming a part hereof.

In the drawing:

Fig. 1 is a front perspective view of a merchandise display holder showing my new design;

Fig. 2 is a front elevational view; and

Fig. 3 is a side elevational view thereof.

I claim:

The ornamental design for a merchandise display holder, substantially as shown.

FRANK V. BRACH.
